UNITED STATES PATENT OFFICE.

ORRIN C. HARRIS, OF NEWPORT, NEW YORK.

CONVERTIBLE CHAIR.

SPECIFICATION forming part of Letters Patent No. 375,934, dated January 3, 1888.

Application filed August 16, 1887. Serial No. 247,081. (No model.)

To all whom it may concern:

Be it known that I, ORRIN C. HARRIS, a citizen of the United States, residing at Newport, in the county of Herkimer and State 5 of New York, have invented certain new and useful Improvements in Convertible Chairs; and I do hereby declare the following to be a full, clear, and exact description of the invention, such as will enable others skilled in the 10 art to which it appertains to make and use the same.

My invention relates to improvements in rocking-chairs provided with adjustable rollers and an adjustable foot-rest, and is more 15 particularly an improvement upon Patent No. 355,819, granted to me January 11, 1887.

The particular construction and arrangement of the various parts of my said invention I will now proceed to point out and describe, reference being had to the accompanying drawings, in which—

Figure 1 is a front elevation of a chair embodying my invention, the rollers being shown adjusted so as to use the same as a roller chair; and Fig. 2 is a side elevation, the legs and rockers being shown in dotted lines, dotted lines also indicating the position of the rollers and foot-rest when the chair is to be used as a 25 rocking chair.

Referring to said drawings, A represents a chair of ordinary construction having legs *a* and rockers *a'*.

B B are brackets secured to the under side of the chair-seat.

C is a shaft mounted in bearings in the brackets B B and provided on one end with a crank-handle, *c*.

D D are short lever-arms secured to the shaft C.

E E are rods having their upper ends bent and pivotally secured to the ends of the lever-arms D D. On the lower ends of the rods E E are mounted rollers F F. The rods E E are connected by braces *e e*. On the upper portion of the braces *e e*, near the rods E E, are formed bearings *e' e'*.

So far as described, the construction of the chair is substantially the same as in my former patent, No. 355,819. The improvement on

said patent consists in the construction and 50 arrangement of the mechanism for operating the adjustable foot-rest, which I will now describe.

G G are pendent arms pivotally secured to the forward round, *b*. 55

H H are slightly-curved rods having their forward ends bent downward and carrying on their lower ends a foot-rest, I.

h h are a series of bolt-holes in the forward bent portions of the rods H H. Said rods H 60 H are pivotally secured to the lower ends of the arms G G by bolts *h' h'*, which are secured in one of the bolt-holes in each rod. The rear portions of the rods H H rest in and are adapted to pass through the bearings *e' e'*. The arms 65 G G are connected by braces K K.

L is a short lever-arm secured to the center of the shaft C.

M is a bent rod pivotally secured at one end to the lever-arm L, and also pivotally secured 70 to its other end to the center of the braces K K, connecting the arms G G.

c' is a stop on one of the legs, which limits the downward forward movement of the crank-handle. 75

To use the chair as a rocking-chair, the handle is turned back to the position shown in dotted lines. This turns the shaft C backward, and through the mechanism described raises the rollers above the rockers and draws the 80 foot-rest under the chair.

To convert the chair into a roller chair, turn the crank-handle forward until it engages with the stop *c'*, when the rollers will be moved below the rockers and the foot-rest be in position for 85 use. By means of the bolt-holes in the rods carrying the foot-rest, said foot-rest can be adjusted to the desired distance from the seat of the chair.

Having thus fully described my invention, I 90 claim as new and desire to secure by Letters Patent—

In a convertible chair provided with rockers, the brackets B B, the shaft C, mounted in bearings in said brackets B B and provided 95 with lever-arms D D and L, the rods E E, pivotally secured to the lever-arms D D and provided with rollers F F, and braces *e e*,

having bearings $e' e'$, in combination with the rods $H H$, mounted in the bearings $e' e'$ and provided with the foot-rest I and bolt-holes $h h$, the pendent arms $G G$, pivotally secured to the rods $H H$ by bolts $h' h'$ and connected by braces $K K$, and the bent rod M , pivotally secured at one end to the braces $K K$ and at its other end to the lever-arm L , all constructed,

arranged, and operating substantially as shown and described.

In testimony whereof I affix my signature in presence of two witnesses.

ORRIN C. HARRIS.
